(57) **CLAIM**

The ornamental design for a tail lamp for a vehicle, as shown and described.

DESCRIPTION

FIG. 1 is a front left perspective top view of a tail lamp for a vehicle according to the present invention.

FIG. 2 is a front left perspective view of the tail lamp shown in FIG. 1.

FIG. 3 is a rear right perspective top view thereof.

FIG. 4 is a rear right perspective view thereof.

FIG. 5 is an enlarged front view thereof.

FIG. 6 is an enlarged rear view thereof.

FIG. 7 is a left side view thereof.

FIG. 8 is a right side view thereof.

FIG. 9 is a top view thereof.

FIG. 10 is a bottom view thereof; and,

FIG. 11 is another front view of the tail lamp shown in FIGS. 1-10, but mounted on a vehicle and with the rest of the vehicle shown in broken lines. The elements shown in broken lines form no part of the claimed design, but are instead included to show environmental aspects thereof.

The claim includes a second embodiment which is a mirror image tail lamp on the opposite side of the vehicle.
